Primary Examiner — Eric Goodman*Assistant Examiner* — Clese Moore, Jr.(74) *Attorney, Agent, or Firm* — Hooker & Habib, P.C.(57) **CLAIM**

The ornamental design of an industrial computer, substantially as shown and described.

DESCRIPTION

FIG. 1 is a top view of a first embodiment of an industrial computer;

FIG. 2 is a bottom view of the first embodiment of the industrial computer shown in FIG. 1;

FIG. 3 is a front view thereof;

FIG. 4 is a rear view thereof;

FIG. 5 is a right side view thereof;

FIG. 6 is a left side view thereof; and,

FIG. 7 is a bottom right perspective view thereof.

The broken lines shown illustrate portions of the industrial computer that form no part of the claimed design.

1 Claim, 5 Drawing Sheets---
